US0D1011382S

(12) **United States Design Patent** (10) **Patent No.:** **US D1,011,382 S**
(45) **Date of Patent:** **** Jan. 16, 2024**

(54) **AERIAL WORK PLATFORM VEHICLE**

(71) Applicants: **JiangSu XCMG Construction Machinery Research Institute LTD., Jiangsu (CN); XCMG FIRE-FIGHTING SAFETY EQUIPMENT CO., LTD., Jiangsu (CN)**

(72) Inventors: **Geng Xue, Jiangsu (CN); He Liu, Jiangsu (CN); Yilin Lu, Jiangsu (CN); Cuijun Jin, Jiangsu (CN)**

(73) Assignees: **JiangSu XCMG Construction Machinery Research Institute LTD., Jiangsu (CN); XCMG FIRE-FIGHTING SAFETY EQUIPMENT CO., LTD., Jiangsu (CN)**

(**) Term: **15 Years**

(21) Appl. No.: **29/813,334**

(22) Filed: **Oct. 28, 2021**

(30) **Foreign Application Priority Data**

Jun. 1, 2021 (CN) 202130330610.9

(51) LOC (14) Cl. **15-04**

(52) U.S. Cl.

(57) **CLAIM**

The ornamental design for an aerial work platform vehicle, as shown.

DESCRIPTION

FIG. 1 is a perspective view of an aerial work platform vehicle showing our new design;

FIG. 2 is another perspective view thereof;

FIG. 3 is a front view thereof;

FIG. 4 is a rear view thereof;

FIG. 5 is a left side view thereof;

FIG. 6 is an enlarged left side view thereof;

FIG. 7 is a right side view thereof;

FIG. 8 is an enlarged right side view thereof; and,

FIG. 9 is a top view thereof.

1 Claim, 9 Drawing Sheets
